United States Patent Office

Des. 180,538
Patented June 25, 1957

180,538

COIN BANK

Joseph Bernard Strauss, Chicago, Ill.

Application April 12, 1956, Serial No. 41,038

Term of patent 3½ years

(Cl. D34—11)

Fig. 1.

Fig. 2.

Fig. 3.

Fig. 1 is a front elevational view of a coin bank showing my new design;

Fig. 2 is a side elevational view thereof; and
Fig. 3 is a top plan view thereof.

I claim:

The ornamental design for a coin bank, substantially as shown.
